UNITED STATES PATENT OFFICE.

LOUIS M. STOLL, OF ST. PAUL, MINNESOTA, ASSIGNOR TO JOHN P. GALBRAITH, OF ST. PAUL, MINNESOTA.

LANTERN.

1,127,695.

Specification of Letters Patent. Patented Feb. 9, 1915.

Application filed May 15, 1914. Serial No. 838,685.

To all whom it may concern:

Be it known that I, LOUIS M. STOLL, a citizen of the United States, residing at St. Paul, in the county of Ramsey and State of Minnesota, have invented certain new and useful Improvements in Lanterns, of which the following is a specification.

My invention relates to lanterns and has for its object to provide a lantern having an incandescent light-giving mechanism effected through the delivery of hot gas, as gasoline or kerosene, and the burning of the same within mantles of usual construction.

To this end I provide a lantern having a receiver for the oil and means directly in said receiver for compressing air within the same upon the body of the oil, together with means for conducting said oil into the lantern and a specially devised generator mechanism for turning said oil into gas and delivering the same to the burner and mantles.

The full objects and advantages of my invention will appear in connection with the detailed description thereof and are particularly pointed out in the claims.

In the drawings, illustrating the application of my invention in one form,—Figure 1 is an elevation view of a lantern embodying my improvements. Fig. 2 is a sectional elevation view taken on a different line from Fig. 1. Fig. 3 is a sectional plan view of the base or oil container. Fig. 4 is an enlarged sectional view of the pumping mechanism.

As illustrated, my lantern comprises a base 10 which is formed of sheet metal and provides an air-tight reservoir 11 into which gasoline or kerosene may be introduced through an inlet 12, closed by plug 13. Upon the top platform 14 of the base 10 is rigidly secured a standard 15 in the form of a pipe, which standard is provided with a control valve 16. The standard 15 is a hollow pipe which communicates at its top with a bow-shaped pipe member 17, from which depend burner tubes 18 and 19 having thereon mantles 20 of any well-known construction. The pipe standard 15 has con-

nected therewith below the bow-piece 17 an air-tube 21, which air-tube extends downwardly through a plate 22 secured to the standard 15 by means of a hub 23 and setscrew 24. The air for admixture with the oil is supplied through tube 21. If additional air outside the generator is deemed advisable it may be obtained through a damper-controlled aperture 25 in plate 22. The plate 22 forms a support for a lantern globe 26 of ordinary construction. The top of the globe 26 is supported in a sheet metal hood 27 carried by a cap 28 which is held in position upon a bolt 29 rigidly connected with the bow-piece 17. Cap, hood, and globe 26 are held rigidly assembled by means of a hand-nut 30 threaded upon the top of bolt 29.

The means for producing air pressure upon the oil within reservoir 11 comprises a casing 31 permanently secured across the chamber 11. One end of casing 31 is closed by a plug 32. The plug 32 is provided with a screw-threaded seat 33 into which may be screwed the threaded end 34 of an ordinary air-chamber 35, the cap 36 of the air-chamber closing the other end of casing 31. The air-chamber is thus removably held within casing 31. The inner portion of the seat cavity 33 is connected by a duct 37 with a cavity 38 in plug 32, in which is threaded a screw-plug 39. From the cavity 38 a duct 40 leads into the interior of reservoir 11. The screw-plug 39 may be caused to seal up duct 40 or open the same to cavity 38, as may be desired. When the pump is employed for applying pressure in chamber 11, the pump will be operated through hand-piece 41 in the usual way, duct 40 having been previously uncovered. After sufficient pressure has been applied within the reservoir 11, the plug 39 is screwed up so as to close duct 40, and a threaded seat 42 on a hand-piece 41 is screwed on to a threaded extension 43 of pump-cap 36 to hold the piston 44 in position in the pump barrel. The pump is therefore carried at all times in the lantern, and yet is so protected that the gasoline or kerosene cannot reach the

piston 44. If it did it would quickly destroy the efficiency of said piston because of the corroding, cutting action of kerosene or gasoline. At the same time the pump may be readily withdrawn for repair, if that should become necessary or desirable. A small tube 45 leads from the bottom of reservoir 11 into the bottom of stand-pipe 15 below valve 16, through which air pressure upon the surface 46 of the oil in reservoir 11 forces such oil into stand-pipe 15 and through valve 16, where the gas is generated and mixed with air from pipe 21.

A separate casing 47 extends within reservoir 11 and is closed from the outside by a stopper 48 upon which is secured a burner member 49. A reservoir 50 within casing 47 is kept filled with alcohol, and when it is desired to light the same, the lighted burner 49 is thrust through the opening 25 to heat the pipes 15 and 17 sufficiently to generate gas when the valve 16 is opened to permit inflow of fuel oil.

The operation and combination of my lantern have been very fully given. By use of the pump 35, air within reservoir 11 is compressed upon the surface 46 so as to produce a high pressure. It is noted that the filling plug 13 is so positioned that the surface 46 will always be lower than the opening of duct 40 into reservoir. With the proper pressure upon the oil surface 46, and after the pipes have been heated by the alcohol pressure, as above pointed out, the valve 16 is turned to the desired extent and the aforesaid pressure causes the fuel oil to rise through tube 45 and valve 16 upon the heated walls of the generator mechanism. The gases generated and mixed with air coming from tube 21 travel through the tubes 18 and 19 and are burned within the mantles 20, giving a brilliant light. The burning of these gases heats tubes 18 and 19 and bow-tube 17 so that an extremely efficient carburetion is accomplished.

I claim:

1. A lantern comprising a reservoir, a pump casing mounted within said reservoir, a closure in the end of the casing within the reservoir having an opening adapted to communicate with the reservoir, an air-pump removably mounted in the casing so as to close said opening to the casing and bring the same into communication with the air-pump, and means for closing said opening to the reservoir.

2. A lantern comprising a reservoir, a pump casing mounted within said reservoir, a plug secured in one end of said casing and extending through a wall of the reservoir, said plug having a screw-threaded seat for holding an air pump and having a cavity communicating with said seat and communicating through the plug with the in-

terior of the reservoir, a screw plug entering said cavity from outside of the reservoir and adapted to close communication with the interior of the reservoir, and an air pump held positioned within the casing by having a projection on the end thereof screwed into said seat.

3. A lantern comprising a reservoir, a cylindrical pump-casing extending horizontally through the upper portion of said reservoir, one end of said casing extending through a wall of the reservoir and being fully open, a plug at the other end of the casing having a screw-threaded seat and having an opening into the reservoir from the cavity of said seat, and an air-pump having a threaded extension screwed into said seat and a cap thereby drawn into engagement with the exposed end of said casing for closing the same.

4. A lantern comprising a base forming a fuel-oil reservoir, a tubular standard rigidly secured upon the top of said base, said standard providing a conduit for the fuel oil, a disk rigidly secured to the standard, a lantern globe upon the disk, a hood slidably mounted upon an extension of the standard, and a hand-nut on said extension for holding the globe and hood removably positioned upon said disk.

5. A lantern comprising a base forming a fuel-oil reservoir, a tubular standard rigidly secured upon the top of said base, said standard providing a conduit for the fuel oil, a disk rigidly secured to the standard, a lantern globe upon the disk, a hood slidably mounted upon an extension of the standard, a hand-nut on said extension for holding the globe and hood removably positioned upon said disk, an air tube extending through the disk and communicating with the tubular standard, and carbureter and burner mechanism supported by said tubular standard and communicating therewith above the entrance of said tube.

6. A lantern comprising a base forming a fuel-oil reservoir, a tubular standard rigidly secured upon and extending vertically from the center of said base, said standard providing a conduit for the fuel-oil, a support secured to the standard, a lantern-globe resting on the support, a hood slidably mounted upon an extension of the standard and having a flaring portion engaging the top of the lantern-globe, and means for removably locking said hood and globe in position upon the support and extension.

7. A lantern comprising a reservoir, a cylindrical pump casing extending horizontally through the upper portion of said reservoir, one end of said casing extending through a wall of said reservoir and being fully open, a plug at the other end of the

casing having a screw threaded seat and having an opening into the reservoir from the cavity of said seat, an air pump having a threaded extension screwed into said seat, 5 and a cap therefor drawn into engagement with the exposed end of said casing for closing the same, a burner having mantles thereon, a hood above said mantle, a globe

surrounding said mantles, and a reflector around said globe.

In testimony whereof I affix my signature in presence of two witnesses.
